UNITED STATES PATENT OFFICE

DENNIS C. O'SHEA, OF CHICAGO, ILLINOIS

PAD

Application filed May 26, 1932. Serial No. 613,720.

This invention relates to improvements in pads and, more especially, such devices adapted to be worn by participants in sports, such as, football, soccer, basketball, and the like.

For the purpose of illustrating my invention, I have here shown the same as embodied in a pad especially adapted for use as a thigh pad. It is to be understood, however, that the invention may be embodied in a pad adapted for protecting any other part of the body. The pad may be worn in any convenient manner as, for example, by attachment to the body with adhesive tape, or the like, or by attachment to the clothing.

One of the features of my invention is the provision of a curved pad with a high degree of flexibility and resiliency and at the same time affording protection not only to the wearer, but also to others coming into contact with the wearer. To this end, I provide a support of resilient material which is given the desired curvature to conform to the thigh of the wearer. This support is completely surrounded with padding, including a layer of padding, such as, felt, or the like, not only on the inside of the support, but also on the outside.

My improved device is light in weight and yet strong and durable.

Other features and advantages of my invention will appear more fully as I proceed with my specification.

In that form of device embodying the features of my invention shown in the accompanying drawing—

Figure 1 is a view in elevation with a portion of the padding broken away; and Fig. 2 is a horizontal sectional view.

As shown in the drawing, the device includes a supporting member, here shown as formed of two substantially rectangular superimposed curved supporting sheets of resilient material attached together at the periphery. These sheets may be made, for example, of fibre or similar material. The outer sheet is indicated by 10 and the inner sheet, by 10^a. These sheets are sewn together around the periphery by the stitching 11. If desired, there may also be provided some auxiliary stitching at other points, for example,

a couple of rows of stitching near the center, as indicated by 11^a.

One of the particular features of my invention is the supporting member just described. This is made of two sheets of superimposed material. Each sheet is substantially rectangular and pre-formed or pre-curved before the sheets are fastened together. One sheet is slightly larger than the other in area so that the two sheets, when curved and fastened together, will have their edges substantially in registry. The two sheets are then fastened together at the periphery as by sewing. This furnishes a very rigid and resilient or springy supporting member for the padding. After the two curved sheets are sewn together, any bending of the same to straighten them tends to shift one sheet upon the other to a certain extent. This shifting is restrained by the stitches and, consequently, there is a tendency for the sheets to separate in the center when they are straightened out. This separation is also restrained by the stitching. This relative shifting of the two curved sheets upon each other, caused by straightening of the same, adds resiliency, elasticity and flexibility which tends to hold the two sheets in their original curved position but yet permits bending or deviation therefrom without danger of injury to the supporting member.

The supporting member, including the two superimposed sheets 10 and 10^a is completely covered by padding. As here shown, such padding includes outer and inner layers of felt 12 and 12^a. These layers of felt have their edges 12^b and 12^c, respectively, projecting a slight distance beyond the edges of the sheets 10 and 10^a and said projecting edges are sewn together outside of the sheets 10 and 10^a by the stitching 13. The projecting edges 12^b and 12^c of the felt sheets 12 and 12^a serve to protect the sharp edges of the sheets 10 and 10^a from injury and also serve to prevent said sharp edges from injuring the wearer or others with whom he comes into contact.

While I have shown and described certain embodiments of my invention, it is to be

understood that it is capable of many modifications. Changes, therefore, in the construction and arrangement may be made without departing from the spirit and scope 5 of the invention as disclosed in the appended claims, in which it is my intention to claim all novelty inherent in my invention as broadly as permissible, in view of the prior art.

What I regard as new, and desire to secure 10 by Letters Patent, is:

1. A device of the character described, including; two substantially rectangular superimposed curved supporting sheets of stiff resilient material attached together at the periphery, said attachment restraining straightening of the sheets by restraining relative shifting thereof; and padding surrounding said supporting sheets.

2. A device as claimed in claim 1, in which the padding consists of two sheets on opposite sides of the supporting sheets, the edges of said padding sheets projecting slightly beyond the edges of the supporting sheets 70 and being attached together.

3. A device as claimed in claim 1, in which the padding consists of two sheets on opposite sides of the supporting sheets, the edges of said padding sheets projecting slightly beyond the edges of the supporting sheets and being attached together by sewing.

In witness whereof, I have hereunto set my hand, this 15th day of February, 1932.

DENNIS C. O'SHEA.
